PHOTOGRAPHIC FLASH UNIT

Fred Hushla, Williamson, N.Y., assignor to Eastman
Kodak Company, Rochester, N.Y., a corporation of
New Jersey

Filed Oct. 5, 1962, Ser. No. 72,000

Term of patent 7 years

(Cl. D61—1)

Fig. 1

FIG. 1 is a front perspective view of a photographic flash unit, showing my new design;

FIG. 2 is a rear perspective view thereof; and

FIG. 3 is a bottom plan view thereof.

The broken-line showing of a flash bulb in FIG. 1 is for illustrative purposes only.

I claim:

The ornamental design for a photographic flash unit, as shown and described.
